UNITED STATES PATENT OFFICE.

JACKSON DENEAL, OF TOLEDO, OHIO, ASSIGNOR OF TWO-FIFTHS TO
STEPHEN BROPHY, OF TOLEDO, OHIO.

MULTIPLE-EXPANSION STEAM-ENGINE.

SPECIFICATION forming part of Letters Patent No. 716,523, dated December 23, 1902.

Application filed March 9, 1901. Serial No. 50,503. (No model.)

To all whom it may concern:

Be it known that I, JACKSON DENEAL, a citizen of the United States, residing at Toledo, in the county of Lucas and State of Ohio, have 5 invented a new and useful Improvement in Multiple-Expansion Steam-Engines, of which the following is a specification.

My invention relates to improvements in multiple-expansion steam-engines. As this 10 class of engines are ordinarily constructed their cylinders are each provided with separate receivers and with inlet and exhaust valves, each having separate operative mechanism, all of which add greatly to the multiplicity of parts, complexity of movement, friction, cost of construction, expense of repair, and the space occupied, by reason whereof engines of the class have not been found economical for general purposes, and more especially for light power or high speed.

The object of my invention is to produce a simple, compact, and effective multiple-expansion engine economical in construction and operation and adapted to a wide range 15 of speed and power, wherein without the use of separate receivers and separate valves and valve-operating mechanism for the expansion-cylinders the steam after being used in one cylinder passes directly into another and 20 is successively reexpanded in a series of cylinders until the expansive force is fully utilized. I accomplish this object by producing an engine having a series of cylinders of progressively-increased diameters, in which, in 25 addition to their ordinary and usual functions, each cylinder excepting the last is a receiver, its exhaust-ports the inlet-ports, and its piston a cut-off valve for the cylinder next 30 succeeding in the series, and by the novel construction and arrangement of parts herein-after described, and illustrated in the drawings.

In the drawings, Figure 1 is a view in vertical longitudinal section of an engine constructed in accordance with my invention. Fig. 2 is a view in cross-section of the same, and Fig. 3 is a sectional plan view of the same.

In the drawings, 1 designates a cylinder-casting provided with bores of progressively-increased diameter to form the piston-valve 45 chamber A, the high-pressure cylinder B, the

intermediate-pressure cylinder C, and the low-pressure cylinder D. In each of the walls which separate the different cylinder-bores there are formed steam-ports 2 and 3, leading 55 in opposite directions from outlets 4 and 5, respectively, for each cylinder, located centrally to the length of the cylinders, but separated by diaphragms 6, to the inlets 7 and 8, respectively, located near the heads of the cylinders next following. Lengthwise of cylinder A is a thickened portion 9 of the wall, which centrally to the length of the cylinder is suitably formed for the attachment of a throttle-valve casing 10, having a steam connection 11, and in the thickened wall 9 are also provided ports 2 and 3, leading from outlets 4 and 5 in the throttle-casing 10 to the inlets 7 and 8, respectively, near the heads of cylinder A. Centrally of its length the low-pressure cylinder D is provided with a boss 12, adapted for the attachment of an exhaust-pipe 13, and separated by a diaphragm 14 are exhaust-ports 15 and 16, leading from the interior of cylinder D through the boss 12 to 75 the exhaust-pipe.

In each of the cylinders B, C, and D is located a piston 17, provided with suitable packing-rings 18. The length of each piston is a little less than one-half the length of its cylinder and its stroke equals its own length, whereby in the middle of each stroke both the central outlets 4 and 5 are closed, and at the end of each stroke they are alternately opened, while the inlets 7 and 8, near the 85 heads 19, are continually left uncovered. The piston-rods 20 are suitably connected to the pistons and in the embodiment of my invention shown in the drawings are provided with slotted yokes 21 to engage with the crank-pins 22. The crank-pins are secured to balanced crank-disks 23, which are mounted upon the crank-shaft 24. The latter is journaled in bearings 25, which are suitably connected to the bed-plate 26 of the engine. The 90 lower ends 27 of the piston-rods are extended to operate as plungers in the pump-barrels 28, which are secured to the bed-plate and pendently supported therefrom in a line with the stroke of the piston-rods and operate as 95 suitable guides for the slotted yoke connections of the piston-rods, thereby obviating the 100

use of pitman connections with the crank-shaft. The pump-barrels may be connected in series or in parallel; and when the engine is used for horseless-vehicle purposes the 5 pumps may be arranged for the water, air, and liquid-fuel supply for the generator.

Within the cylinder A there is located a piston-valve 30, having piston-rod 31 connected thereto, which is coupled, by means of 10 a pitman 32, to a crank-pin 33, which is secured to a crank-disk 34, mounted upon the end of the crank-shaft. The piston-valve 30 is provided with packing-rings 35 and is adapted to close both of the outlets 4 and 5 15 of cylinder A in the middle of its stroke and to open and close them alternately at the end of its stroke.

36 designates a throttle-valve, which is housed within the casing 10 and is provided 20 with ports 37 and 38, adapted to connect with outlets 4 and 5 of the throttle-casing, whereby steam may be admitted into the cylinder A at both ends or at either end thereof by turning the throttle-valve and closing one of the 25 ports 4 or 5 of the throttle-casing by the laps 39 of the valve, which latter are disposed upon each side of the ports 37 and 38. The valve 36 is provided with a stem 40, suitably journaled and packed in the casing 10, and the 30 stem is provided with a lever 41 for operating the valve.

In length the piston-valve 30 is adapted to cover the outlet-ports 4 and 5 of the cylinder A when in the middle of its stroke, and the 35 crank-pin 33 is secured to the disk 34 at a radius adapted to limit the stroke to the length of the valve and at ninety degrees from the crank-pin 22 for the piston of cylinder B. By this arrangement when the piston of cylinder 40 B is at the end of its upper stroke the piston-valve 30 will be in the center of its stroke in position to close both outlets 4 and 5 of cylinder A, and at the end of its stroke in either direction one end of the valve will be central 45 to the diaphragm separating the outlets 4 and 5. It is also apparent that when the piston crank-pin 22 of cylinder B is slightly past its upper center the piston-valve 30 will begin to open outlet 4 of cylinder A and that it will 50 be fully opened and closed again during the downward stroke of the piston of cylinder B and that in like manner port 5 of cylinder A will be opened and closed during its upward stroke. The crank-pins 22 of the pistons of 55 cylinders B and D are secured to their respective crank-disks 23 at points slightly varying from one hundred and eighty degrees from the crank-pin of cylinder C to give the crank-pin of cylinder C a slight lead over the crank-pins of both of cylinders B and D, so as to 60 prevent coincidence of their centers. The ports 2 and 3, the outlets 4 and 5, and inlets 7 and 8 are progressively increased in area from the high-pressure to the low-pressure 65 cylinders in proportion to the cylinders which they supply. Thus constructed it is apparent that the operation of the piston of cylin-

der B does not differ materially from the ordinary double-acting one-cylinder engine and that it in turn operates as a valve for cylinder C, opening and closing its inlet-ports alternately, thereby operating the piston of cylinder C as a double-acting engine in reverse stroke with the piston of B, and that the piston of C operates in turn as a valve for cylinder D, alternately opening and closing its inlet-ports, thereby operating its piston in reverse stroke to the piston of cylinder C and in substantial unison with the piston of cylinder B. It is also manifest that the engine 80 can be started or reversed either by manipulation of the throttle-valve or by opening both ports of the throttle and turning the fly-wheel 42 in the desired direction of movement, and by closing either one of the throttle-ports the 85 engine may be operated as a single-acting engine from the ends of the cylinders to which the open port leads. When running as a double-acting engine, it is apparent that the valve-piston of cylinder A is balanced and 90 offers no resistance excepting its friction and that the piston of each cylinder operates as a cut-off valve for the next cylinder in the series, that while there is some back pressure in all of the cylinders excepting cylinder A 95 the reaction from compression is equal to such back pressure, and that there is a constant overbalance of working pressure equal to the expansive force of the steam. By attaching a condenser to the exhaust an equal 100 percentage of the steam-pressure below atmospheric pressure is utilized, as in other engines of the kind, while all the receivers, valves, eccentrics, and reversing mechanism ordinarily employed for operating the expansion- 105 cylinders are entirely eliminated by my construction, and by utilizing the cylinders as receivers and adapting their pistons to operate as valves as well as perform their ordinary 110 functions I have produced a simple and compact engine of the kind, economical in construction and operation, adapted to all speeds and powers, and more especially have made it possible to economically employ the principle of multiple expansion for light power 115 and high speed. By making the piston of cylinder A of the same length as the pistons of the other cylinders and the radius of its crank the same as the other piston-cranks it will operate as a cut-off valve for cylinder B 120 and the piston of B will for a portion of its stroke travel on the expansion of the steam, and in proportion as the radius of the crank and the length of the valve-piston is reduced the cut-off will be increased until cylinder B 125 can be made to operate substantially on live steam throughout its stroke. For medium pressures a series comprising a high, intermediate, and low pressure cylinder is sufficient to expand the steam to atmospheric 130 pressure; but for extreme high pressures and high speed a shorter stroke and an increased number of cylinders may be economically employed. The number of cylinders in the se-

ries may also be reduced without departing from the principle of my construction. By leaving off the low-pressure cylinder D, adapting C as a low-pressure cylinder, and adjusting the length and stroke of the piston of valve-cylinder A so as to shorten the cut-off of cylinder B, as hereinbefore described, such definite part of the expansion of the steam may be utilized in the latter cylinder, as that cylinder C will complete its expansion to atmospheric pressure or below it if a condenser is used.

Having thus fully described my invention, what I claim to be new, and desire to secure by Letters Patent, is—

1. In a double-acting multiple-expansion engine, the combination of a series of cylinders of progressively-increased diameters respectively, connected together side by side in the order of their progression, with their axes in the same plane, comprising a valve-cylinder, a high-pressure cylinder, and one or more expansion-cylinders, a pair of ports in each of the division-walls between the cylinders, leading from centrally-located openings in the smaller cylinder, in opposite directions, to openings in the larger cylinder, adjacent to its heads, that are exhaust-ports for the smaller cylinder and inlet-ports for the larger, exhaust-ports in the low-pressure cylinder, located centrally of its length and opening into an exhaust, a steam connection for the valve-cylinder, provided with a pair of branch connections opening into opposite ends of the valve-cylinder, a piston in each cylinder, adapted as a valve to close the exhaust-ports of its cylinder in the middle of its stroke, and open them alternately at the end of each stroke, the pistons being connected with cranks of a common shaft, the crank for the piston of the valve-cylinder being set at ninety degrees from the centers of the other cranks, which alternate at one hun-

dred and eighty degrees from each other, and a manual valve in the steam connection, adapted to progressively open or close either or both the branch connections to the valve-cylinder separately or simultaneously, substantially as shown and described.

2. In a double-acting engine, the combination with a pressure-cylinder provided with a pair of exhaust-ports located centrally of its length, and with a piston adapted to close the exhaust-ports during the middle of its stroke and open them alternately at the end of each stroke, of a valve-cylinder connected side by side with the pressure-cylinder, with the axes of the cylinders in the same plane, a pair of ports in the division-wall between the two cylinders, leading respectively from centrally-located openings in the valve-cylinder in opposite directions to openings in the pressure-cylinder, adjacent to its heads, that are exhaust-ports for the valve-cylinder and inlet-ports for the pressure-cylinder, a piston for the valve-cylinder, adapted to close its outlet-ports in the middle of its stroke and open them alternately at the end of each stroke, the pistons of both cylinders being connected to cranks of a common shaft set at ninety degrees apart, a steam connection for the valve-cylinder, a valve-chamber in the steam connection, having a pair of ports respectively leading therefrom into opposite ends of the valve-cylinder, a valve in the valve-chamber, having a pair of ports adapted to be progressively brought into or out of full coincidence, each, with a port of the valve-chamber, separately or simultaneously, substantially as shown and described.

In witness whereof I have hereunto set my hand this 25th day of February, A. D. 1901.

JACKSON DENEAL.
